(57) **CLAIM**

The ornamental design for shoe sole, as shown and described.

DESCRIPTION

FIG. 1 is a top, left side perspective view of the shoe sole of my new design;

FIG. 2 is a front elevation view thereof;

FIG. 3 is a right side elevation view thereof, the left side being a mirror image;

FIG. 4 is a rear elevation view thereof; and,

FIG. 5 is a bottom view thereof.

No claim is made to the upper surface bounded by broken lines.

1 Claim, 3 Drawing Sheets

FIG. 3

FIG. 4

FIG. 5
